UNITED STATES PATENT OFFICE.

MAX LEPOW, OF NEWARK, NEW JERSEY, ASSIGNOR TO THE H. A. WILSON COMPANY, OF NEWARK, NEW JERSEY, A CORPORATION OF NEW JERSEY.

DESIGN FOR A FINGER RING.

Application filed May 19, 1928 Serial No. 26,771. Term of patent 3½ years.

To all whom it may concern:

Be it known that I, MAX LEPOW, a citizen of Russia, residing at 956 18th Avenue, Newark, in the county of Essex, State of New Jersey, have invented a new, original, and ornamental Design for a Finger Ring, of which the following is a specification, reference being had to the accompanying drawing, forming part thereof.

Figure 1 is a perspective view of a finger ring showing my new design,

Fig. 2 is a cross sectional view taken on line 2—2 of Fig. 1.

I claim:

The ornamental design for a finger ring, as shown.

MAX LEPOW.
